UNITED STATES PATENT OFFICE.

HOMER D. MARTINDALE, OF MIDDLETOWN, OHIO.

APPARATUS FOR MAKING PULP OR THE LIKE.

Application filed February 17, 1927. Serial No. 168,912.

This invention relates to improvements in apparatus for making pulp.

In the accompanying drawings which serve for illustrating the invention:

5 Fig. 1 is a plan view of a stock beater or breaker of the usual construction to which the improvements comprised in the invention have been applied, the improvements being shown in section;

10 Fig. 2 is a sectional view in elevation of the complete apparatus, taken on line 2—2 of Fig. 1;

Fig. 3 is a sectional view in elevation taken on line 3—3 of Fig. 1;

15 Fig. 4 is a sectional view corresponding to Fig. 3, showing a modification;

Fig. 5 is a view in perspective of a perforated backfall used in connection with the apparatus;

20 Fig. 6 is a detail view of the drain for conducting water and salvaged stock back into the beater.

The objects attained in the invention consist in a simple apparatus used in connection with an ordinary stock beater or

25 breaker, preferably equipped with a perforated backfall, for removing foreign materials, or junk, from the stock in process of reduction to prevent accumulation of such 30 material in the beater tub and the resulting interference with the processes of reduction.

Thus with the improved apparatus as herein set forth, less and cheaper machinery is required for making pulp, and reduction 35 is speeded up and increased output is obtained.

As here shown, the improved apparatus comprises a stock beater 1 of the usual construction, including as shown in Figs. 1 and

40 3, a mid-feather 2, a beater roll 3, perforated backfall 4, and extraction chest 5 for finished pulp, the beater as a whole being below the floor line 6.

The means for removing the junk from 45 the beater consist of a channel 7, formed in the bottom of the beater tub on the receiving side of the beater roll and extended through the mid-feather, across the bottom to the opposite wall of the tub, and upwardly outside the wall to the floor level, as best shown in Fig. 3.

Heavy foreign substances—scraps of iron, gravel, sand, etc.,—settle in the bottom of the channel 7, the movement of the stock in

the beater being constantly over the channel, 55 all such material settles by gravity to the lowest level in the tub.

A series of buckets 8, on an endless chain 9, directed over wheels 10, supported on an overhead structure 11, traverse the channel 60 7 and act to scoop out the junk and deliver it in a container 12, which is here shown as supported on wheels 13, on a track 14, for convenience in dumping the container for removing the junk therefrom.

65 A water line 15 and drain line 16 are connected to the junk container for flushing it to recover salvageable pulp carried up with the junk, and returning it to the beater, the drain pipe discharging into channel 7, or 70 direct into the beater, as may be desired.

To further facilitate reclaiming salvageable material from the junk, the walls of the container 12, as here shown, are perforated, the discharge through the walls being upon a 75 deck 17 disposed over the beater tub and having a drain 18 into channel 7.

The perforated backfall, as best shown in Fig. 2 in its relation to the beater roll, acts to separate fine pulp from the mass of pulp 80 in process of reduction in the beater, the fine pulp passing through the grading apertures in the backfall into the chest 5, being removed from the chest through a pipe 19.

The modified construction illustrated in Fig. 4 consists in extending the channel 7* 85 from one side of the beater to the other, and structural modifications for operating the buckets for removing the junk as indicated in the drawing. In the modified form the junk removing mechanism is applicable to stock beaters or breakers in which no hollow mid-feather is used.

90 From the foregoing description and the drawings it will be seen that the reduction of pulp will be continuous without the frequent interruption incident to shutting down the reduction apparatus for removing the junk from the beater as in the usual practice.

Having described my invention, I claim: 100

1. A pulp reduction apparatus including in combination, a stock beater, a channel extended across the bottom to an adjacent wall of the beater tub and upwardly outside the wall, and acting to receive foreign 105 materials separated by gravity from stock in process of reduction in the beater, and a series of devices, as buckets, operably con-

nected for traversing the channel for removing the accumulation of said material therein.

2. A pulp reduction apparatus including in combination, a stock beater, a channel extended through the mid-feather, across the bottom to the adjacent wall of the beater tub and upwardly outside the wall, and acting to receive foreign materials separated by gravity from stock in process of reduction in the beater, and a series of devices, as buckets, operably connected for traversing the channel for removing the accumulation of said material therein.

15 3. A pulp reduction apparatus including in combination, a stock beater, a channel extended across the bottom to an adjacent wall of the beater tub and upwardly outside the wall, and acting to receive foreign materials separated by gravity from stock in process of reduction in the beater, a series of devices, as buckets, operably connected for traversing the channel for removing the accumulation of said material therein, a track and wheeled 20 container operable on the track for receiving the material from said devices.

4. A pulp reduction apparatus including in combination, a stock beater, a channel extended across the bottom to an adjacent wall 30 of the beater tub and upwardly outside the wall, and acting to receive foreign materials separated by gravity from stock in process of reduction in the beater, a series of devices, as buckets, operably connected for traversing 35 the channel for removing the accumulation of said material therein, a container having apertured walls for receiving the material from said devices, a water line connection for flushing the container, and a drain con-

nexion for returning water and salvaged 40 stock discharged through said walls to the beater.

5. A pulp reduction apparatus including in combination, a stock beater, a channel extended across the bottom to an adjacent wall 45 of the beater tub and upwardly outside the wall, and acting to receive foreign materials separated by gravity from stock in process of reduction in the beater, a series of devices, as buckets, operably connected for 50 traversing the channel for removing the accumulation of said material therein, a container for receiving the material removed from the beater by said devices, means for flushing the container for removing salvaged 55 stock therefrom and a deck over the beater acting to drain the water and stock discharged from the container back into the beater tub.

6. A pulp reduction apparatus including 60 in combination, a stock beater, a channel extended across the bottom to an adjacent wall of the beater tub and upwardly outside the wall, and acting to receive foreign materials separated by gravity from stock in process 65 of reduction in the beater, a series of devices, as buckets, operably connected for traversing the channel for removing the accumulation of said material therein, a container for receiving the material removed 70 from the beater by said devices, means for flushing the container for removing salvage stock therefrom and a deck including a drain leading to said channel acting to return water and stock discharged from said receptacle to the beater tub. 75

In testimony whereof, I affix my signature.
HOMER D. MARTINDALE.
